UNITED STATES PATENT OFFICE

REUBEN A. SKOGLUND, OF DANVILLE, ILLINOIS

HAT HOLDING DEVICE

Application filed October 22, 1928. Serial No. 314,153.

This invention relates to hat holding devices.

With the present forms of devices for holding hats and the like, the structures of such devices require that they be secured to vertical surfaces such as walls, and they usually are in the form of hooks or the like which merely support but do not hold the hats. Such devices, accordingly, are not adapted 10 for use against horizontal surfaces such as the tops of motor vehicles and the like, nor are they adapted for use in motor vehicles or the like in which use they would be subjected to considerable movement.

15 An important object of the present invention is to provide a hat holder which not only supports but holds the hat in proper position thereon, and which may be used in any desired position, such as horizontal, vertical, 20 angular, etc.

A further object is to provide a hat holder which is adapted for use in motor vehicles, railway coaches and similar places where the device is subjected to various movements 25 which would dislodge hats from the present types of hat holding devices.

A further object is to provide a device of the character referred to which is simple in construction and cheap to manufacture, the 30 device being adapted to be made of a single piece of material such as relatively stiff wire.

Other objects and advantages of the invention will become apparent during the 35 course of the following description.

In the drawings I have shown several embodiments of the invention. In this showing,

40 Figure 1 is a side elevation, Figure 2 is a bottom plan view, and Figure 3 is a perspective view of a modified form of the device.

Referring to Figures 1 and 2, the numeral 10 designates the device as a whole which is 45 shown as being formed of a single piece of

relatively stiff wire. The body of the device is coiled centrally thereof as at 11 to form an eye adapted to receive a screw 12 or other fastening element. The device may be arranged in any desired position, and in the 50 drawings it is shown as being vertically arranged and attached to a horizontal support 13, such as the inside of the top of a motor vehicle or the like.

Outwardly of the eye 11, the device is provided with a pair of similar diverging arms 14 which terminate at their outer ends in hat engaging elements 15. Each of the engaging elements is illustrated as being arcuate in form and comprising inner and outer parallel 55 portions 16 and 17, the ends of the wire from which the device is made terminating substantially centrally of the outer portions 16 and adjacent the extremities of the arms 14 as indicated at 18.

The form of the device illustrated in Figure 3 is similar to that previously described and need not be referred to in detail. The modified form of the device also is provided with the hat engaging members 15, the outer portions of which are preferably covered with a fabric or similar covering 19. In place of the coiled central portion 11 previously described, the modified form of the device is preferably provided with a looped portion 20 having an open side 21 between the arms 14, whereby it will be apparent that the looped portion may be snapped into position over the shank of a screw which has been 70 previously partially inserted in position.

From the drawings it will be obvious that the eye portion in each form of the device is in a plane substantially at right angles to the plane of the arms 14, and that the hat engaging elements 15 are in a plane substantially parallel to the plane of the eye portion in each form of the device. This arrangement provides a simple, compact construction 75 which is cheap and easy to manufacture and 80

which may be quickly secured in proper position.

The operation of the device is as follows:

The device may be attached either to a vertical, horizontal or angular surface, as may be desired, and is particularly adapted for use for holding hats in motor vehicles, railway coaches and the like. For example, the device may be arranged vertically and secured against the inside of the top of a motor vehicle for holding a hat with the brim thereof flat against the top of the vehicle. The hat engaging members 15 are preferably arranged a sufficient distance apart to permit them to engage the insides of hats of relatively large size, and it will be apparent that the arms 14 may be sprung inwardly to permit the engaging members to be inserted within hats of smaller size.

The arms 14 are preferably relatively long whereby they engage within the upper portion of the crown of a hat, and when so arranged, the brim of the hat is adapted to lie flat against the supporting surface 13 whereby the hat will be steadied to assist in holding it in position against dislodgement, particularly when the device is used in motor vehicles. The device is adapted to be placed in position merely by inserting a screw through the eye 11 and driving the screw into the supporting structure.

In the form of the device shown in Figure 3, a screw may be partially inserted in the supporting structure, and the looped portion 20 snapped into position over the shank of the screw, whereupon the screw may be tightened into position. Similarly, the device readily may be removed merely by loosening the screw to disengage the head thereof from the looped portion 20, whereupon the latter may be moved laterally with respect to the screw to permit the screw to snap outwardly through the open side 21 of the looped portion 20.

The fabric or similar covering 19 may be employed if desired to protect the inner surfaces of the hat. It also will be apparent that the shape of the engaging members 15 may be altered according to individual conditions.

It is to be understood that the forms of the invention herewith shown and described are to be taken as preferred examples of the same and that various changes in the shape, size and arrangement of parts may be resorted to without departing from the spirit of the invention or the scope of the subjoined claim.

I claim:

A hat holding device comprising a body formed of a single piece of resilient wire coiled centrally of its length to provide a relatively flat eye adapted to receive a fastening element, said wire on opposite sides of said eye being bent to form arms lying in a plane substantially at right angles to the plane of

said eye and diverging equally on opposite sides of the axis thereof, the wire being bent at the ends of said arms to form hat engaging members extending to equal extents on opposite sides thereof and each of which is provided with concentric inner and outer portions of substantial length connected at their ends by loops formed in the wire, the inner and outer portions of said hat engaging members lying in a common plane substantially at right angles to the axis of said eye.

In testimony whereof I affix my signature.

REUBEN A. SKOGLUND.
